TRANSMISSION SYSTEM

Roswell H. Herrick, Oak Park, Ill., assignor to
 Associated Electric Laboratories, Inc., Chicago,
 Ill., a corporation of Delaware

Application August 14, 1939, Serial No. 290,086

14 Claims. (Cl. 179—170)

The present invention relates generally to improvements in two-way signal current transmission systems of the type in which signal controlled switching circuits are provided for partially or completely blocking, under certain conditions, certain of the signal current channels included therein, and more particularly to improvements in telephone substation circuits having incorporated coupled signal current channels for the transmission of incoming and outgoing signal currents.

When separate signal current transmission channels are incorporated in a substation circuit for transmitting outgoing and incoming signal currents between the associated transmitting and receiving means and the line extending thereto, the channels must necessarily be electrically and acoustically coupled at the respective ends thereof, thus effectively forming a closed loop over which side tone currents may be transmitted to the receiving means during operation of the transmitting means and vice versa. Moreover, if signal current amplification is introduced in one or both of the channels so that the energy gain around the closed loop exceeds the energy losses therearound, oscillation of the system may occur to produce interference commonly known as singing. In order to obviate these difficulties, various arrangements have been used for partially or completely blocking each signal channel when not in use or, alternatively, for introducing losses in each channel, when not in use, sufficient to prevent singing and substantially to reduce the flow of side tone currents. Such arrangements must necessarily be so designed that speech clipping at the beginning and end of each signaling interval is prevented.

It is an object of the present invention, therefore, to provide telephone substation apparatus of the character described wherein the elimination of singing and side tone suppression are accomplished in a positive, reliable and improved manner and wherein speech clipping is substantially prevented.

It is a further object of the invention to provide improved substation apparatus of the character described wherein a single sound translating device is arranged to be used as both the signal transmitting means and as the signal receiving means.

It is another object of the invention to provide an improved two-way signal current transmission system of the character described wherein the elimination of singing and side tone suppression

are accomplished in a positive and reliable manner with a minimum of circuit apparatus.

In the illustrated embodiment of the invention there is provided a telephone substation circuit 5 which is adapted to be connected to a line and comprises a sound translating device which is arranged to serve both as signal transmitting and signal receiving means. This device is coupled to the associated line through a signal transmission system which comprises a pair of channels for transmitting signal currents between the line and the device in opposite directions. The transmission system has incorporated therein signal current controlled switching means for 10 selectively controlling the signal current transmission efficiencies of the respective channels in accordance with the direction of signal current flow therethrough. More particularly, the transmission system comprises a pair of vacuum tube amplifiers which are respectively included in the two signal current channels, the amplifier inserted in one of the channels having connected in tandem therewith a voltage reducing circuit. This circuit, in cooperation with the amplifier 15 included in the other channel, functions to control the switching means in a manner such that the other channel, which is normally blocked or inactive, is rendered active and the channel in which the voltage reducing circuit is included 20 is rendered inactive in response to signal currents incoming to the substation over the associated line. To this end there is provided a control circuit which is coupled to each of the two channels, means being embodied therein for providing 25 two control voltages in response to signal currents traversing the transmission system. The arrangement is such that the voltage reducing circuit mentioned above and the amplifier included in the other channel function to unbalance 30 the two control voltages only when signal currents traverse the said other channel. These two control voltages are impressed across the windings of a differentially wound control device whereby the control device is caused to operate 35 only when the control voltages are unbalanced. This control device is arranged to control the operation of a set of switching contacts which are provided for controlling the signal current transmission efficiencies of the two channels. 40

Further features of the invention pertain to the particular arrangement of the circuit elements whereby the above-mentioned and additional operating features are attained.

The novel features believed to be characteristic of the invention are set forth with particu- 45

50

55

larity in the appended claims. The invention, both as to its organization and method of operation, together with further objects and advantages thereof, will best be understood by reference to the specification taken in connection with the accompanying drawing, the single figure of which illustrates a telephone substation circuit having incorporated therein the features of the invention as briefly outlined above.

Referring to the drawing, the substation circuit there illustrated comprises a sound translating device 10 coupled to a line extending to the bracketed terminals 11 by means of a pair of signal current transmission channels 12 and 13, the channel 13 being utilized to transmit incoming signal currents from the line to the sound translating device 10 and the channel 12 being utilized to transmit outgoing signal currents from the sound translating device 10 to the line terminals 11. The sound translating device 10 is preferably in the form of a loud speaker of the moving coil type having embodied therein a signal current coil 14 which is arranged selectively to be coupled to the input circuit of a vacuum tube amplifier 15 included in the channel 12 or the output circuit of a vacuum tube amplifier 16 included in the channel 13 through the operation of switching contacts controlled by a relay 20 which is included in a control circuit 25. More particularly, the amplifier 15 comprises a vacuum tube 31 of the pentode type having input electrodes 32 and 33 normally coupled to the loud speaker 10 through a transformer 34 and output electrodes 33 and 35 included in an output circuit which comprises the primary winding of a coupling transformer 36 and a source of anode current 37. For the purpose of providing a bias voltage between the input electrodes 32 and 33, there is provided a cathode biasing circuit which includes a resistor 38 shunted by a signal current by-passing condenser 39. The amplifier 16 included in the signal current transmission channel 13 similarly comprises a vacuum tube 40 of the well-known pentode type having input electrodes 41 and 42 coupled to the line terminals 11 through a coupling transformer 43 and output electrodes 41 and 44 arranged to be coupled to the moving coil 14 of the speaker 10 through a coupling transformer 45. A cathode biasing circuit comprising a resistor 46 shunted by a signal current by-passing condenser 47 is provided for biasing the control grid 42 to the correct negative potential with respect to the cathode 41. Anode current is supplied to the anode 44 of the tube 40 from the source 37 through the primary winding of the transformer 45. As illustrated in the drawing, the screen grids respectively embodied in the tubes 31 and 40 are connected directly to the positive terminal of the source 37. Preferably these tubes are of the character commercially known as the Type 47 tube having incorporated therein cathodes of the filamentary type to insure quick heating when energized from a suitable alternating current source. The cathodes 33 and 41 of the two tubes are connected in parallel across the secondary winding of a voltage dropping transformer 46 having its primary winding arranged to be connected to any available source of commercial frequency current.

The switching control circuit 25 comprises, in addition to the relay 20, a pair of gaseous discharge tubes 47 and 48 and a pair of associated potentiometer or voltage dividing resistors 49

and 50 which are connected in parallel across the source 37. Preferably the discharge tubes 47 and 48 are in the form of neon lamps. A lamp of this type possesses the characteristic of being nonconductive until a predetermined voltage commonly known as the break down voltage is impressed across the terminals thereof, at which time the lamp is rendered conductive and the resistance thereof is reduced from an exceedingly high value to a relatively small value. After a lamp of this character is rendered conductive, the voltage across the terminals thereof must be reduced to a value somewhat less than the break down value before the discharge through the lamp is extinguished. The discharge device 47 is connected across the upper adjustable portion of the potentiometer 49 in series with the winding 21 of the relay 20 and a resistor 51. The setting of the potentiometer 49 is such that the voltage impressed across the terminals of the discharge device 47 over the circuit just described is of less magnitude than the voltage required to render the device conductive or to sustain a discharge through the tube. For the purpose of increasing the voltage across the terminals of the discharge device 47 when outgoing signal currents traverse the transmission channel 12, this device is coupled to the output circuit of the amplifier 15 over a path including a condenser 52 and a current limiting resistor 53. With this arrangement the tube 47 is rendered conductive during alternate half cycles of signal currents traversing the output circuit of the amplifier 15 so that a pulsing direct current is caused to traverse the winding 21 of the relay 20. In order to smooth out the fluctuations of this current, a smoothing condenser 54 is provided which is connected in shunt with the series connected resistor 51 and winding 21. The discharge device 48 is similarly connected across the lower adjustable portion of the potentiometer 50 in series with a resistor 55 and the winding 22 of the relay 20, the potentiometer 50 being so adjusted that the voltage impressed across the terminals of the device 48 is of a slightly less magnitude than the voltage required to render this device conductive or to sustain a discharge there-through. In order to render the discharge tube 48 conductive during alternate half cycles of signal currents traversing the incoming signal current channel 13, this device is coupled to the output circuit of the amplifier 16 over a path comprising a condenser 56 and a current limiting resistor 57. Fluctuations of the pulsating direct current traversing the winding 22 of the relay 20 when the tube 48 is conductive are reduced through the provision of a smoothing condenser 58 connected in shunt with the series connected winding 22 and resistor 55.

The switching elements controlled by the relay 20 comprise a pair of normally closed contacts 23 and 24 arranged to short-circuit the secondary winding of the transformer 45, and an armature 26 which in cooperation with the contact 24 is arranged to open the indicated short-circuiting path and to close a path for short-circuiting the primary winding of the coupling transformer 34. An additional armature 27 is provided for short-circuiting the winding 21 of the relay 20 when this relay is operated, thereby to render the relay slow to release in a well-known manner.

In order to assist in the unbalancing of the voltages impressed across the relay windings 21 and 22 of the control circuit 25 when signal currents traverse the transmission system in one di-

rection, there is provided a voltage reducing or losser circuit 60 which is connected in tandem with the amplifier 15. Briefly described, this circuit comprises four series resistance arms 61, 62, 63 and 64 and a parallel or conjugate arm 65. With the resistance elements 61 to 65, inclusive, arranged in this manner, signal currents incoming over the line connected to the terminals 11 traverse the primary winding of the coupling transformer 43, the resistance elements 64 and 62 and a parallel circuit, one branch of which includes the resistor 65 and the other branch of which includes the resistor 61; the secondary winding of the transformer 36 and the resistor 63 in series. Due to the voltage drops across the elements 61, 62, 63 and 64 and the shunt path afforded by the resistor 65, only a portion of the available signal voltage impressed across the incoming terminals of the circuit 60 appears across the secondary winding terminals of the transformer 36.

Referring now more particularly to the operation of the circuit, it will be understood that the transmission system is conditioned for operation when the primary circuit of the transformer 46 is energized so that current is conducted through the filamentary cathodes of the amplifier tubes 31 and 40. At this time the discharge tubes 47 and 48 are nonconductive so that no current traverses either of the two windings of the relay 20. Accordingly, this relay occupies its restored position so that the contact springs 23 and 24 are in engagement to short-circuit the secondary winding of the transformer 45, thus effectively blocking signal current transmission through the channel 13 to the loud speaker 10. With the apparatus in this condition, if sound waves impinge upon the diaphragm of the loud speaker 10, a signal voltage is developed in the moving coil 14 which is impressed through the transformer 34 across the input electrodes of the amplifier tube 31. The resulting amplified signal currents appearing in the output circuit of the amplifier 15 are transmitted through the coupling transformer 36 and the voltage reducing circuit 60 to the line connected to the terminals 11 and are transmitted over this line to the distant substation for reproduction. A portion of the amplified signal voltage is also impressed, through the transformer 43, upon the input electrodes of the amplifier tube 40. Due to the coupling afforded by the circuit comprising the condenser 52 and the resistor 53 and extending between the transmission channel 12 and the control circuit 25, the potential of the lower terminal of the discharge tube 47 is varied in accordance with variations in the potential of the anode 35 included in the tube 31. Accordingly, during signal current transmissions the potential of the lower terminal of the discharge tube 47 is alternately increased and decreased during each cycle of the signal voltage. Each time this potential is lowered the voltage drop across the tube 47 is increased, since the upper terminal of this tube is maintained at a substantially constant potential determined by the voltage of the source 37. With the potentiometer 49 properly adjusted, each increase in the voltage across the tube 47 renders this tube conductive so that current is caused to traverse the space current path of the tube, the resistor 54, the winding 21 and the adjustable portion of the potentiometer resistor 49. Immediately the discharge tube 47 is ionized the voltage drop developed across the winding 21 and the resistor 54 lowers the voltage across the tube to a value below

the arc sustaining value and hence the tube is deionized to interrupt the current flow through the winding 21. During the opposite half cycles of the signal voltage, the voltage across the terminals of the discharge tube 47 is decreased to a value lower than the normal bias value and hence the tube is not rendered conductive. Thus, a pulsating direct current is caused to traverse the winding 21 of the relay 20 during signal current flow through the channel 12. The condenser 54 tends to smooth the pulsations of current through the resistor 51 and the winding 21. This condenser is, however, of relatively high impedance as compared with the series impedance of the resistor 51 and the winding 21, whereby the major portion of the signal currents delivered to the control circuit from the channel 12 are caused to traverse the winding 21.

The signal currents transmitted through the coupling transformer 43 are amplified by the amplifier 16 to cause the discharge tube 48 to be rendered conductive during alternate half cycles of the signal current coincident with the periods when the tube 47 is rendered conductive. Thus, during each cycle of the signal current, the potential of the anode 44 is increased and decreased producing a like increase and decrease in the potential of the upper terminal of the discharge tube 48. Since the lower terminal of the tube 48 is at a fixed positive potential determined by the voltage of the source 37, the voltage drop across this tube is increased during each decrease in the potential of the upper terminal thereof. This increase in the voltage across the tube 48 is sufficient to cause the tube to break down so that direct current is caused to traverse the space current path of the tube, the resistor 55 and the relay winding 22. Due to the voltage developed across the series connected winding 22 and resistor 55, the voltage drop across the tube 48 is almost immediately lowered to a value below the arc sustaining value. Accordingly, the tube is deionized to interrupt the current flow through the winding 22. Each time the potential of the upper terminal of the tube 48 is increased during an alternate half cycle of the signal voltage, the voltage across this tube is decreased to a point below the normal bias value. Accordingly, the tube 48 is not rendered conductive. From the foregoing explanation, it will be apparent that the winding 22 is energized with a pulsating direct current when signal currents traverse the channel 12. This pulsating current is smoothed by the condenser 58 which is of relatively large impedance as compared with the series impedance of the winding 22 and resistor 55, thereby to prevent the signal currents traversing the coupling circuit comprising the condenser 56 from being by-passed around the winding 22. The circuit constants are such that the voltages developed across the two windings 21 and 22 are substantially equal in magnitude. Since these windings are differentially related and are of identical construction, the fluxes developed by the currents traversing the windings cancel. Accordingly, the relay 20 does not operate so long as signal currents developed in response to sound waves impinging upon the diaphragm of the loud speaker 10 are traversing the transmission channel 12. The channel 13 is, therefore, effectively blocked during outgoing signal current transmission and, as a result, oscillation of the system is prevented and the transmission

of side tone currents back to the moving coil 14 of the loud speaker 10 cannot occur.

With the transmission system conditioned for operation, signal currents incoming thereto over the associated line are caused to traverse the primary winding of the coupling transformer 43 and the secondary winding of the transformer 36 in the manner previously explained. Due to the voltage step-down action of the circuit 60 and the voltage reducing operation of the transformer 36, the signal voltage appearing across the channel 12 in the output circuit of the amplifier 15 is quite small. Accordingly, the potential fluctuations of the lower or control terminal of the discharge tube 47 are of such small magnitude that this tube is not rendered conductive. The amplified signal voltage developed across the output circuit of the amplifier 16 is, however, of sufficient magnitude to cause the break down of the discharge tube 48 during alternate half cycles of the signal voltage. Accordingly, only the winding 22 of the relay 20 is energized in response to signal currents incoming to the substation circuit. When this winding is first energized the relay 20 immediately operates to short-circuit, at its armature 27, the winding 21, thereby to render itself slow to release and to restrict the flow of transient currents through the winding 22, which currents might be reproduced as clicks by 30 the loud speaker 10. Upon operating, the relay 20 also completes, at its armature 26 and the associated contact 24, an obvious path for short-circuiting the primary winding of the transformer 34, thereby to block or render inoperative the signal transmission channel 12. At the contact springs 23 and 24, the relay 20 opens the path normally short-circuiting the secondary winding of the transformer 45, whereby the incoming signal currents may be transmitted through this transformer to the moving coil 14 of the loud speaker 10 to be reproduced as sound waves in the usual manner. It will be noted that with the relay 20 operated the transmission channel 12 is completely inoperative. Accordingly, local oscillation of the system is prevented and complete side tone suppression is achieved. With this arrangement it is impossible for a user of the illustrated substation apparatus to break in upon the speech train being received over the channel 13. With the winding 21 of the relay 20 short-circuited the release time of this relay is sufficiently long to prevent the restoration of the relay during the short intervals between syllables of speech. Thus, hang-over periods are provided so that voice currents received substantially without interruption serve to maintain the transmission channel 12 inactive and the channel 13 active.

When the incoming signal currents are interrupted for a time interval exceeding the release period of the relay 20, this relay restores to reestablish, at the contact springs 23 and 24, the path short-circuiting the secondary winding of the transformer 45 and to interrupt, at the armature 26 and the contact spring 24, the path short-circuiting the primary winding of the transformer 34. Thus, the channel 13 is blocked or rendered inactive and the channel 12 is reconditioned to transmit outgoing signal currents to the associated line. Upon restoring, the relay 20 also opens, at its armature 27, the path short-circuiting its winding 21, thereby to condition itself for fast operation. When energized, this relay operates with sufficient rapidity to prevent

any substantial clipping of the voice currents received at the beginning of a speech train and representing the first syllables of the train.

Although the invention has been described with reference to an arrangement wherein the transmission channels not in use are completely blocked, it is contemplated that a partial blocking of these channels during the inactive periods thereof may be used if desired. To this end, a 10 resistor may be serially included in the channel blocking path, preferably by connecting the same between the contact spring 24 and the junction connection between the primary winding of the transformer 34 and the secondary winding of the transformer 45. With a resistor of proper 15 resistance value connected in this manner, the coupling between the channels through the resistor may be held to a sufficiently low value substantially to prevent singing and to insure adequate side tone suppression, at the same time providing an arrangement whereby conversation "break-ins" may occur.

While there has been described what is at present considered to be the preferred embodiment of the invention, it will be understood that various modifications may be made therein, and it is contemplated to cover in the appended claims all such modifications as fall within the true spirit and scope of the invention.

What is claimed is:

1. A transmission system comprising a pair of channels for transmitting signal currents in different directions, and means comprising a voltage reducing circuit connected in one of said channels and amplifying means connected in the other of said channels for substantially changing the signal current transmission efficiency of at least one of said channels.

2. A transmission system comprising a pair of channels for transmitting signal currents in different directions, circuit means operative to provide two balanced control voltages in response to signal currents traversing said system, means comprising a voltage reducing circuit connected in one of said channels for unbalancing said voltages only when signal currents traverse said system in one direction, and means controlled in accordance with the relative magnitudes of said control voltages for substantially changing the signal current transmission efficiency of at least one of said channels.

3. A transmission system comprising a pair of channels for transmitting signal currents in different directions, circuit means operative to provide two balanced control voltages in response to signal currents traversing said system, means comprising a voltage reducing circuit connected in one of said channels for unbalancing said voltages only when signal currents traverse said system in one direction, a relay including a pair of differentially related windings across which said control voltages are respectively impressed, whereby said relay is normally in one circuit controlling position and operates to a second circuit controlling position in response to the unbalancing of said voltages, and means controlled by said relay for substantially changing the signal current transmission efficiency of at least one of said channels.

4. A transmission system comprising a pair of channels for transmitting signal currents in different directions, a signal current amplifier included in each of said channels, circuit means operative to provide two balanced control voltages in response to signal currents traversing said

system, means comprising a voltage reducing circuit connected in one of said channels and the signal current amplifier included in the other of said channels for unbalancing said voltages only when signal currents traverse said system in one direction, and means controlled in accordance with the relative magnitudes of said control voltages for substantially changing the signal current transmission efficiency of at least one of said channels.

5. A transmission system comprising a pair of channels for transmitting signal currents in different directions, a signal current amplifier included in each of said channels, circuit means operative to provide two balanced control voltages in response to signal currents traversing said system, means comprising a voltage reducing circuit connected in one of said channels and the signal current amplifier included in the other of said channels for unbalancing said voltages only when signal currents traverse said system in one direction, a relay including a pair of differentially related windings across which said control voltages are respectively impressed, whereby said relay is normally in one circuit controlling position and operates to a second circuit controlling position in response to the unbalancing of said voltages, and means controlled by said relay for substantially changing the signal current transmission efficiency of at least one of said channels.

6. A transmission system comprising a pair of channels for transmitting signal currents in different directions, a signal current amplifier and a voltage reducing circuit included in one of said channels, said amplifier and said circuit being connected in tandem in the order named in the direction of signal current transmission through said one channel, a second signal current amplifier included in the other of said channels, a control circuit coupled to said one channel at a point between said first-named amplifier and said voltage reducing circuit and to said other channel at a point following said second amplifier, said circuit including means for providing two balanced control voltages in response to signal currents traversing said system, means comprising said voltage reducing circuit and said second amplifier for unbalancing said voltages when signal currents traverse said other channel, and means operative in response to the unbalancing of said voltages for substantially reducing the signal current transmission efficiency of said one channel.

7. A transmission system comprising a pair of channels for transmitting signal currents in different directions, a signal current amplifier and a voltage reducing circuit included in one of said channels, said amplifier and said circuit being connected in tandem in the order named in the direction of signal current transmission through said one channel, a second signal current amplifier included in the other of said channels and including an input circuit coupled through said voltage reducing circuit to the output circuit of said first-mentioned amplifier, whereby signal currents traversing said one channel are transmitted through said second amplifier, a control circuit coupled to said one channel at a point between said first-named amplifier and said voltage reducing circuit and to said other channel at a point following said second amplifier, said circuit including means for providing two control voltages in response to signal currents traversing said system, means comprising said voltage reducing circuit and said second amplifier for unbalancing said voltages when signal currents trav-

erse said other channel, switching means normally effective substantially to reduce the signal current transmission efficiency of said other channel, and means operative in response to the unbalancing of said voltages for causing said switching means to increase the signal current transmission efficiency of said other channel and substantially to reduce the signal current transmission efficiency of said one channel.

10. 8. In a transmission system including a pair of channels for transmitting signal currents in different directions, a network for controlling the signal current transmission efficiency of at least one of said channels, said network comprising, in combination, a pair of discharge devices, each of said devices being nonconductive until voltage of a predetermined magnitude is impressed across the terminals thereof, circuit means for impressing signal voltages appearing across one of said channels upon one of said devices and for impressing signal voltages appearing across the other of said channels upon the other of said devices, thereby to render said devices conductive, a pair of control circuits respectively including said discharge devices and each energized only when the discharge device included therein is rendered conductive, a control device including a pair of differentially related windings respectively included in said control circuits, whereby said control device is caused to operate from one position to another when only one of said discharge devices is rendered conductive, and switching means controlled by said control device for controlling the signal current transmission efficiency of at least one of said channels.

9. In a transmission system including a pair of channels for transmitting signal currents in different directions, means coupling said channels together to provide substantially equal signal voltages across predetermined points of said channels in response to signal currents traversing said system in one direction and substantially unequal signal voltages across said predetermined points of said channels in response to signal currents traversing said system in the other direction, a circuit network comprising a pair of discharge devices, each of said devices being normally nonconductive and being characterized by a predetermined break down voltage at which it is rendered conductive, circuits respectively including said devices and also including means for impressing biasing voltages across said discharge devices which are less in magnitude than said break down voltage, circuit means for impressing signal voltages appearing across said predetermined point of one of said channels upon one of said discharge devices, and for impressing signal voltages appearing across said predetermined point of the other of said channels upon the other of said discharge devices, whereby both of said discharge devices are rendered conductive during alternate half cycles of said signal voltages when signal currents traverse said system in said one direction and only one of said discharge devices is rendered conductive when signal currents traverse said system in said other direction, and switching means controlled in accordance with the currents traversing said devices for controlling the signal current transmission efficiency of at least one of said channels.

10. In a transmission system including a pair of channels for transmitting signal currents in different directions, means coupling said channels together to provide substantially equal signal voltages across predetermined points of said

channels in response to signal currents traversing said system in one direction and substantially unequal signal voltages across said predetermined points of said channels in response to signal currents traversing said system in the other direction, a circuit network comprising a pair of discharge devices, each of said devices being normally nonconductive and being characterized by a predetermined break down voltage at which it is rendered conductive, circuits respectively including said devices and also including means for impressing biasing voltages across said discharge devices which are less in magnitude than said break down voltage, circuit means for impressing signal voltages appearing across said predetermined point of one of said channels upon one of said discharge devices, and for impressing signal voltages appearing across said predetermined point of the other of said channels upon the other of said discharge devices, whereby both of said discharge devices are rendered conductive during alternate half cycles of said signal voltages when signal currents traverse said system in said one direction and only one of said discharge devices is rendered conductive when signal currents traverse said system in said other direction, a control device including a pair of differentially related windings respectively included in said circuits, whereby said control device is caused to operate from one position to another when only one of said discharge devices is rendered conductive, and switching means controlled by said control device for controlling the signal current transmission efficiency of at least one of said channels.

11. A transmission system comprising a pair of channels for transmitting signal currents in different directions, a signal current amplifier and a voltage reducing circuit included in one of said channels, said amplifier and said circuit being connected in tandem in the order named in the direction of signal current transmission through said one channel, a second signal current amplifier included in the other of said channels and including an input circuit coupled through said voltage reducing circuit to the output circuit of said first-mentioned amplifier, whereby signal currents traversing said one channel are transmitted through said second amplifier, a circuit network comprising a pair of discharge devices, each of said devices being normally nonconductive and being characterized by a predetermined break down voltage at which it is rendered conductive, control circuits respectively including said discharge devices and also including means for impressing biasing voltages across said discharge devices which are less in magnitude than said break down voltage, circuit means for impressing signal voltages appearing across said one channel at a point between said first-named amplifier and said voltage reducing circuit upon one of said discharge devices and for impressing signal voltages appearing across said other channel at a point following said second amplifier upon the other of said discharge devices, means comprising said voltage reducing circuit and said second amplifier for unbalancing said signal voltages when signal currents traverse said other channel, whereby both of said discharge devices are rendered conductive during alternate half cycles of said signal voltages when signal currents traverse said one channel and only one of said discharge devices is rendered conductive during alternate half cycles of said signal voltages when signal currents traverse said other channel, where by both of said discharge devices are rendered conductive during alternate half cycles of said signal voltages when signal currents traverse said one channel and only one of said discharge devices is rendered conductive during alternate half cycles of said signal voltages when signal cur-

rents traverse said other channel, switching means normally effective substantially to reduce the signal current transmission efficiency of said other channel, and means operative in response to an unbalancing of said voltage for causing said switching means to increase the signal current transmission efficiency of said other channel and substantially to reduce the signal current transmission efficiency of said one channel.

12. A transmission system comprising a pair of channels for transmitting signal currents in different directions, a signal current amplifier and a voltage reducing circuit included in one of said channels, said amplifier and said circuit being connected in tandem in the order named in the direction of signal current transmission through said one channel, a second signal current amplifier included in the other of said channels and including an input circuit coupled through said voltage reducing circuit to the output circuit of said first-mentioned amplifier, whereby signal currents traversing said one channel are transmitted through said second amplifier, a circuit network comprising a pair of discharge devices, each of said devices being normally nonconductive and being characterized by a predetermined break down voltage at which it is rendered conductive, control circuits respectively including said discharge devices and also including means for impressing biasing voltages across said discharge devices which are less in magnitude than said break down voltage, circuit means for impressing signal voltages appearing across said one channel at a point between said first-named amplifier and said voltage reducing circuit upon one of said discharge devices and for impressing signal voltages appearing across said other channel at a point following said second amplifier upon the other of said discharge devices, means comprising said voltage reducing circuit and said second amplifier for unbalancing said signal voltages when signal currents traverse said other channel, whereby both of said discharge devices are rendered conductive during alternate half cycles of said signal voltages when signal currents traverse said one channel and only one of said discharge devices is rendered conductive during alternate half cycles of said signal voltages when signal currents traverse said other channel, a control device including a pair of differentially related windings respectively included in said circuits, whereby said control device is caused to operate from one position to another when only one of said discharge devices is rendered conductive, and switching means controlled by said control device for controlling the signal current transmission efficiency of at least one of said channels.

13. Telephone substation apparatus adapted to be connected to a line and comprising signal transmitting and receiving means, a pair of signal current channels for transmitting incoming signal currents to said receiving means and outgoing signal currents to said line, an amplifier in each of said channels, a voltage reducing circuit included in one of said channels, and means comprising said voltage reducing circuit and the amplifier of the other of said channels for substantially changing the signal current transmission efficiency of at least one of said channels in response to signal currents traversing one of said channels.

14. Telephone substation apparatus adapted to be connected to a line and comprising signal

transmitting and receiving means, a pair of signal current channels for transmitting incoming signal currents to said receiving means and outgoing signal currents to said line, a signal current amplifier and a voltage reducing circuit included in one of said channels, said amplifier and said circuit being connected in tandem in the order named in the direction of signal current transmission through said one channel, a second signal current amplifier included in the other of said channels, a control circuit coupled to said one channel at a point between said first-named amplifier and said voltage reducing cir-

5 cuit and to said other channel at a point following said second amplifier, said circuit including means for providing two control voltages in response to signal currents traversing said channels, means comprising said voltage reducing circuit and said second amplifier for unbalancing said control voltages when signal currents traverse said other channel, and means operative to change the signal transmission efficiency of at least one of said channels in response to the unbalancing of said control voltages.

ROSWELL H. HERRICK.
